United States Patent Office.

CHARLES S. HALL, OF ROCHESTER, NEW YORK.

Design No. 4,629, dated February 7, 1871.

DESIGN FOR A SHOW-CARD.

The Schedule referred to in these Letters Patent and making part of the same.

I, CHARLES S. HALL, of Rochester, in the county of Monroe and State of New York, have invented a certain new and original "Design for an Advertising-Card," of which the following is a specification.

My invention relates to a show-card for advertising thrashers and separators.

The central portion of the card is occupied by a cut of a thrasher and separator, upon either side of which are placed portraits of Joseph Hall, late of Rochester, N. Y., and Charles S. Hall, of the same place, one or both, as desired.

The upper corners of the card contain representations of an eagle surmounting a shield, both being surrounded by a scroll or wreath, as indicated in the accompanying photograph.

In a convenient place or places upon the card the words "Chas. S. Hall, Proprietor of the old Joseph Hall Agricultural Works, South Water St., Rochester, N. Y.," are located with or without the characters "No. 10," before the name of the street, together with other imprint or imprints which may be necessary to advertise my particular business.

What I claim as my invention is—

The design for an advertising-card, substantially as set forth.

CHAS. S. HALL.
